JUG

Richard L. Weckman, Perrysburg, Ohio, assignor to Owens-Illinois, Inc., Toledo, Ohio, a corporation of Ohio

Filed May 23, 1966, Ser. No. 2,394

Term of patent 14 years

(Cl. D58—5)

The portion of the jug lying beneath the handle has a circular cross sectional configuration.

The characteristic features of this design reside in the configuration shown in full lines on the drawing.

I claim:

The ornamental design for a jug, substantially as shown and described.
